UNITED STATES PATENT OFFICE.

GODFREY H. TOCHTROP, OF PORTAGE DES SIOUX, MISSOURI.

DESIGN FOR A HARROW-FRAME.

SPECIFICATION forming part of Design No. 25,427, dated April 21, 1896.

Application filed March 9, 1896. Serial No. 582,484. Term of patent 14 years.

To all whom it may concern:

Be it known that I, GODFREY H. TOCHTROP, a citizen of the United States, residing at Portage des Sioux, in the county of St. Charles and State of Missouri, have invented a certain new and original Design for Harrow-Frames, of which the following is a full, clear, and exact specification, reference being had to the accompanying drawings, forming 10 a part thereof, in which---

Figure 1 is a top plan view, and Fig. 2 is a side elevation.

The invention relates to a new and original design for harrow-frames; and it consists in 15 the shape and configuration illustrated in the drawings.

The design resides in the obliquely-arranged elongated substantially S-shaped bars A, which bars are intersected by the cross-bars B, one of said bars having formed on

one end an eye b, while at its opposite end projects the hooked extension b'. At one end of the frame are the rectangular plates C, said plates being arranged parallel relative to each other and having on their outer ends 25 the fanciful crook projections c.

The essential feature of the design is the arrangement of the bars A, cross-bars B, and plates C.

What I claim is—

The design for a harrow-frame, substantially as herein shown and described.

In testimony whereof I hereunto affix my signature, in presence of two witnesses, this 27th day of February, 1896.

GODFREY H. TOCHTROP.

Witnesses:

HUGH K. WAGNER,
F. R. CORNWALL.
